JOHN M. HOTHERSALL, OF BROOKLYN, NEW YORK, ASSIGNOR TO AMERICAN CAN COMPANY, OF NEW YORK, N. Y., A CORPORATION OF NEW JERSEY

GAUGING MECHANISM

Application filed November 23, 1928. Serial No. 321,364.

This invention relates to a gauging and checking attachment for presses and particularly to a device of this character which will accurately and positively position and hold an irregular shaped piece of sheet material for a press operation.

The principal object of the invention is the provision of a simple and efficient gauging and checking device, fully automatic in its operation and readily adaptable to any standard form of press which will receive in any one of a number of possible positions a piece of sheet material, non-symmetrical as to either or both its horizontal x axis or its vertical y axis and properly place and hold the same within the press operating elements, such gauging and checking action being automatically determined by the outline or shape of the piece of material and the relative position in which it is received.

A further important object of the invention is the provision of a gauging and checking device which is operated in connection with an automatic press feeding mechanism and one which will perform its operations of gauging and checking during the travel of the piece of sheet material from a receiving position to the press operating elements.

Another and highly important object of the invention is the provision of a gauging and checking device for operation upon a piece of sheet material, which consists of a minimum number of working parts and one in which movement of the parts occurs by reason of direct connection with the automatic press feeding mechanism.

The invention contemplates a new principle of gauging and checking whereby a definite shape of a piece of sheet material capable of only one correct axial position within the press operating elements is placed in this correct position, regardless of how it is received within the apparatus, which may be in one of a number of possible axial positions, this variety of possible receiving posi-

tions being dependent upon the non-symmetrical character of the piece of sheet material and the promiscuous manner of introducing the same into the machine.

Numerous other objects and advantages of the invention will be apparent as it is better understood from the following description, which, taken in connection with the accompanying drawings, discloses a preferred embodiment thereof.

Referring to the drawings:

Figure 1 is a top plan view of the lower part of a press mechanism and of certain press feeding devices connected therewith, parts being broken away to more clearly illustrate the apparatus;

Fig. 2 is a longitudinal sectional view of the press mechanism and feeding devices, the view being taken along the broken line 2—2 in Fig. 1;

Fig. 3 is a transverse sectional view taken along line 3—3 in Fig. 1;

Fig. 4 is a fragmentary sectional plan view of a portion of the feed mechanism, the view being taken along the line 4—4 in Fig. 2;

Figs. 5, 6, and 7 are fragmentary plan views of the lower parts of the press mechanism and the press feeding and gauging devices associated therewith, said views showing the piece of sheet material in different positions.

In some classes of sheet metal manufacture the entire sheet of material used for the manufacture of a particular object is not utilized and often there remains a relatively small, irregularly shaped, scrap piece. It is customary for manufacturers to subsequently feed such pieces into some form of press mechanism for obtaining smaller objects known as "recoveries". It is to the automatic feeding of these scrap pieces to press operating elements that the present invention is primarily directed.

There is disclosed in the drawings for the purposes of illustration a particular shape or piece of sheet material such as is obtained dur-

ing the blanking of strips used in the manufacture of tin can parts. In such blanking operation a sheet of material is cut into strips and two small scrap pieces are removed from the ends of alternate strips. Such a scrap piece therefore throughout the present description and also in the claims will be referred to as an "end piece".

Such an end piece is non-symmetrical as to both its horizontal x axis and its vertical y axis and is selected for purposes of illustrating the present invention because of its non-symmetrical character. The principle of the present invention, however, has a broader application and is equally well adapted to the gauging and checking of other shaped pieces of material which may or may not be non-symmetrical as to both axes.

The horizontal or x axis referred to is an imaginary axis, designated in the drawings by the line $x-x$ and is the axis which must be brought into coincidence with the longitudinal center of the cutting die parts of the press operating elements in order to obtain the recovery from the end piece with the greatest efficiency of cutting. In like manner, the vertical y axis, which is designated in the drawings by the line $y-y$, is an imaginary axis which must be brought into coincidence with the transverse or lateral center of said die parts.

An end piece 21 as disclosed in the drawings has a relatively narrow edge a opposite an edge c on different sides of the x axis, and a notched edge b opposite an edge d on different sides of the y axis. In the machine of the present invention the end piece 21 may be introduced in any one of four different positions and the gauging and checking device 20 will operate automatically to properly present said piece to the said die parts as will be fully explained.

In Fig. 1 the end piece 21 disclosed at the left hand side is in one of these positions, edge a being toward the top of the sheet, edge d at the left hand side. A second position is illustrated in Fig. 5 where the end piece 21 has its c edge at the top, its d edge at the left hand side. Fig. 6 discloses the end piece 21 in a third position, this being with its c edge at the top and its b edge at the left. In the fourth possible position, illustrated in Fig. 7, the a edge is toward the top, the b edge toward the left.

This variety of positions in which the end piece 21 is received means that the gauging and checking devices must variously shift (laterally and longitudinally) said end piece as it brings the same in proper coincidence relative to the die parts. As viewed in the drawings, the top edge of said end piece 21 and the left or rear edge of the same constitute the edges of reference, that is to say, these are the edges first engaged in gauging.

Referring to Fig. 2, the press comprises a

supporting frame or bolster plate 22 which acts as a support, not only for the press mechanism but also for the feeding mechanism and the gauging and checking devices. A die block 23 is mounted upon and carried by the bolster plate 22 and in turn supports a die plate 24 which carries a cut edge 25 of the die parts of the press operating elements. The cut edge 25, die plate 24 and die block 23 are held in fixed position on the bolster plate by means of bolts 26 (see Fig. 1). A forming pad 27 is mounted for slight vertical movement interiorly of the cut edge 25 and carries the ordinary pins 28 passing through a rubber buffer 29 and extending down through the die plate 24. The parts 23, 24, 25, 27, 28 and 29 constitute an ordinary standard type of die mechanism of a punch press.

As illustrated in Fig. 2, the punch members of the press operating elements are carried by a punch block 31 mounted on any form of standard slide 32 which is raised and lowered in usual manner by mechanism not shown. The punch block 31 carries a punch member or male die 33 which is formed with a cut edge 34 and an interior panel block 35 which also constitutes a knockout pad. The knockout pad is independently raised and lowered by a reciprocating knockout rod 36 operating within the punch member 33.

By cooperation of the punch cut edge 34 and the die cut edge 25, the piece 21 is operated upon to form any suitable recovery piece 37. As disclosed in Fig. 2, the said piece 37 as formed by the cooperation of the punch and die parts is raised with the raising of the punch member. The remaining skeleton 38 of the piece 21 is stripped from the cut edge 34 of the punch by means of a chute 41 supported by uprights 42 secured to the bolster plate 22. Upon operation of the knockout pad 35, the formed recovery piece 37 is forced outwardly from the punch and falls into the chute 41 from which it is delivered.

It is customary in presses of the type illustrated for the upper surface of the die to be at an angle to the horizontal, and in like manner the punch member operates along a line which is at an angle to the vertical. This relatively inclined position is illustrated in Fig. 3 wherein the piece 21 is shown at a distinct angle to the horizontal. By this positioning of operating parts of the press, the work will fall by gravity onto the inclined surface of the chute 41 and will not fall through a clearance opening 43 (Fig. 2) in the floor of the chute 41. This clearance opening permits free movement of the punch member therethrough.

Mounted upon the bolster plate 22 is a bracket 44 which extends to one side of the die mechanism and is formed with parallel spaced side walls 45. The upper part of the bracket constitutes a feed table 46 over which

the pieces 21 are adapted to be moved as they are introduced into the apparatus and are fed to the press operating elements. A primary feeding device and a secondary feeding device are mounted for operation between the side walls 45 of the bracket 44, the former acting as a means for introducing the end pieces 21 upon the table 46 and the latter constituting an automatic feed for the said pieces to the punch and die mechanism of the press operating elements.

The primary feed embodies a chain conveyor 47 operating over an idler sprocket 48 rotatably mounted on a horizontal shaft 49 secured in suitable bearings 51 formed in the table 46, and over a drive sprocket 52 secured to a drive shaft 53 mounted for rotation within bearings 54 formed in the side walls 45 of the bracket 44 (see Figs. 3 and 4). The drive sprocket 52 is constantly rotated in any suitable manner, not shown. The chain conveyor 47 carries a series of spaced flights 55. The outer end of the chain conveyor 47 passes over any suitable idler sprocket, not shown, which may or may not be a part of an independent machine. The upper run of the chain conveyor 47 moves within a slot 56 formed in the table 46 and is in alignment with the upper surface of the table 46. End pieces 21 are fed to the upper surface of the chain conveyor 47 in any suitable manner and in any one of the four positions previously mentioned, a flight 55 of said conveyor engaging and moving a said piece toward the right, as viewed in Figs. 1 and 2.

As the end piece 21 is moved toward the right and over the upper surface of the table 46 by the chain conveyor 47, it reaches a point where the chain passes downwardly over the sprocket 48 and clears the rear edge of the said end piece 21. At this point the end piece is engaged by the secondary feeding mechanism for further movement through the apparatus. The secondary feeding apparatus comprises a slide member 57 formed with oppositely projecting shoulders 58 operating within longitudinal slots 59 formed in the table 46 (see Fig. 3). The slide 57 carries a pair of spaced spring-held dogs 61 pivotally mounted thereon and normally held with their front edges raised above the surface of the table by means of leaf springs 62. The forward part of the chain conveyor 47 extends forwardly of the end of the slide member 57 when the latter is in rear position and said slide 57 is slotted at 60 to prevent interference.

As the end piece 21 is released from the action of the chain conveyor 47, the slide 57 is in the rear position, this being toward the left as viewed in Figs. 1 and 2. In this position, one of the spring dogs 61 is adjacent the rear edge of the said end piece and upon the next forward movement of the slide 57

and the dog 61 the said piece 21 is moved toward the right. As illustrated in Fig. 1, the piece 21 is being released from the influence of one of the flights 55 of the chain conveyor 47, and the lower rear dog 61 is directly back of the edge *d* of the said piece 21. If a said piece 21 is brought into the apparatus in a different position; for example, if the edge *c* is upward and the edge *b* in the rear, the upper dog 61 would be adjacent the rear edge *b*.

As illustrated in Fig. 2, the slide 57 is connected at its forward end to a block 63, which carries a horizontal shaft 64 forming a pivotal connection with a link 65, pivotally secured to the upper end of a lever 66, in turn pivoted upon a fixed stud 67 carried by one of the side walls 45 of the bracket 44. The drive shaft 53 is a crank shaft having a crank portion 71 located between the bearings 54. The lever 66 is pivotally connected at 68 with a connecting bar 69 which embraces the crank portion 71 of the shaft 53. Rotation of the drive shaft 53 through the described connections reciprocates the lever 66 and by means of its connection with the slide 57 causes the latter to move back and forth within the guideways of the table 46 formed by the slots 59.

The forward end of the slide 57 carries a pair of spaced spring-pressed dogs 73 pivoted at 74 so that their forward edges will normally be held above the surface of the table 46 by means of leaf springs 75 (see Figs. 1 and 2). With the slide 57 in its rear position, the spring-pressed dogs 73 are at the left of an end piece 21 which has previously been moved from its first received position into its second position.

As illustrated in Fig. 1, the first received position A is where the said end piece 21 is brought to rest by the action of the chain conveyor 47. Station B indicates the position where the end piece 21 is brought to rest after a forward reciprocation of the slide 57 and after one of the dogs 61 has engaged the rear edge of the said end piece and carried it with the forward travel of the slide 57, toward the right, as viewed in the drawings. C indicates the third position of rest of the end piece 21, this being the operating station of the press mechanism. Station B is the station where the beginning of the gauging and checking operation takes place. No operation is performed upon the end piece 21 as it is moved from station A to station B, other than the mere shifting of its position longitudinally between the two stations. At station B the end piece is positioned adjacent the gauging and checking mechanism and the gauging and checking operation takes place as the end piece is conveyed from station B to station C.

The end piece 21 at rest at station B is engaged by one of the dogs 73 and moved

toward the right to station C with the forward movement of the slide 57. In a manner similar to that previously described for the dogs 61, one or other of the dogs 73 will engage the rear edge of the end piece 21 to move the same toward the station C. As illustrated in Fig. 1, the upper dog 73 is in position to engage a rear edge *d* of the end piece 21 at station B.

Owing to the inclined position of the table 46 and the upper surface of the slide 57, which is inclined according to the inclination of the upper surface of the die parts of the press, as previously described, the upper edge of the strip 21, as shown in Fig. 1, rests by gravity against a sliding bar 76 which constitutes a part of the gauging and checking device, which will be hereinafter more fully explained.

As the end piece 21 is conveyed over the surface of the table 46, it passes beneath a top guide rail 77 carried by a yoke 78, the arms 79 of which are pivoted about a stub shaft 81 carried by a bracket 82 held by bolts 83 to the rear wall 45 of the bracket 44 (see Figs. 1 and 3). The weight of the yoke 78 and the top guide rail 77 is sufficient at all times to hold the end pieces 21 down against the upper surface of the table 46 and the slide 57 during the movement of the said end pieces 21 from stations A to B and stations B to C.

As the slide 57 moves backward, the forward dogs 73 pass beneath one of the end pieces 21 positioned at station B and the rear dogs 61 pass beneath one of the end pieces 21 held at station A. During this passing of the respective dogs beneath the positioned end pieces 21, the respective springs 62 and 75 permit pivoting of the said dogs 61 and 73 and the forward edges of the same are depressed sufficient to clear the positioned end pieces. To prevent rear movement of the end piece 21 from the station B during the backward movement of the said slide 57, there is provided a spring-pressed dog 84 pivoted at 85 to the top guide rail 77, a leaf spring 86 permitting depression of the said dog during the forward movement of the end piece 21 therebeneath. Said dog 84 and its associated parts are illustrated in dotted lines in Fig. 2, and in full lines in Fig. 1.

The gauging and checking devices consist of working parts moving with the forward movement of the end piece 21 and engaging certain edges of the end piece according to its relative position, whereby the end piece is shifted laterally and longitudinally relative to the gauging and checking device until the said end piece is brought into an exact aligned position at station C. In the mechanical arts the term "checking" relates to the final accurate positioning of an object after the same has been roughly positioned by gauging devices. In the present use of the terms gaug-

ing and checking devices, the gauging of the end piece describes generally the moving and rough positioning of the said end piece, and the term "checking" describes, the final, exact, and accurate alignment of the same relative to the die mechanism. 70

As illustrated in Fig. 3, the shaft 64 is extended toward the rear side wall 45 of the bracket 44 and is pivotally engaged by the hub 87 of a stem 88 secured to a sliding plate 89 having movement over an auxiliary surface 91 of the table 46. A slot 92 formed in the surface 91 permits movement of the stem 88 back and forth with the reciprocating movement of the slide 57. A guide bar 93 is secured on the surface 91 of the table 46 by means of screws 94 and is spaced from a shoulder 95 formed in the table 46 adjacent the surface 91 and constitutes a slideway for the plate 89, and also for the sliding bar 76 which is secured thereto. The upper edge of the bar 76 during such movement slides within a groove formed in a bar 90 supported by the bracket 82. 75 80 85

The gauging and checking device is mounted upon the sliding plate 89 and therefore, moves in unison with the moving of the slide 57 of the secondary feeding mechanism, arms 96 and 97 thereof being pivotally mounted on a stud 98 carried by the sliding plate 89 95 (see Fig. 3). A collar 99 is keyed by a pin 100 to the upper end of the stud 98 and prevents displacement of the said arms 96 and 97. The arm 96 carries a projection 101 and an extension 102 on which is mounted a cam following roller 103 pivoted about a pin 104. A coil spring 105 extends between a pin 106 carried by the arm 96 and the pin 100, and tends to hold said arm 96 in what will be termed a closed position. 100 105

The arm 97 carries a pin 107 forming a pivot for a finger 108 adapted normally to rest against one end of the arm 97. The finger 108 also carries a cam following roller 109 pivoted about a pin 111. Said finger 108 is held in normal position by means of a spring 112 extending between a pin 113 carried by the arm 97 and a pin 114 carried by the finger 108. The arm 97 is normally held in closed position relative to the pivot pin 98 by means of a spring 115 extending between a pin 116 carried by the arm 97 and the pin 100. 110 115

By means of the described parts 96 and 97 and the associated mechanism, it should be evident that the gauging and checking device consists of movable members bodily carried with the sliding movement of the plate 89 and independently movable about the pivot pin 98 against the actions of the springs 105 and 115 carried by the respective arms 96 and 97. 120 125

When the slide 57 is in its rear position, the sliding plate 89 is also in a rear position and the arms 96 and 97 carried thereby are 130

positioned at the station B as illustrated in Fig. 1. At such time, the cam rollers 103 and 109 of the respective arms 96 and 97 have engaged an outer cam face 117 formed on the guide bar 93 and in such position the arms 96 and 97 are held against the action of the springs 105 and 115 in an open position where the projection 101 of the arm 96 and the finger 108 associated with the arm 97 are out of contact with the upper edge of the end piece 21. In this open position, the forward extremity of the projection 101 and the finger 108 are back of the forward face of the sliding bar 76, as clearly illustrated in Fig. 1. It should be understood that the projection 101 of the arm 96 is freely movable within a slot 118 cut through the sliding bar 76, as indicated in Figs. 1 and 3. Starting from the position illustrated in Fig. 1, the end piece 21 at station B, which rests by gravity with its upper edge *c* against the sliding bar 76, will be moved toward the right upon the next forward reciprocation of the slide 57. Simultaneously with this movement, the gauging and checking device will also be moved toward the right.

As the cam following roller 109 approaches the forward end of the guide bar 93, it engages a cam inclined surface 119 of the said guide plate 93 and the spring 115 draws the arm 97 downward, the same pivoting about its pivot pin 98. During such movement finger 108 is held locked against the end of arm 97 by means of spring 112 and both finger 108 and arm 97 move as a unit. As the forward movement continues, the cam following roller 103 passes over the incline 119 and in similar manner the spring 105 draws the arm 96 downward, it also pivoting about the pivot pin 98. This moving of the arms 96 and 97 causes engagement of parts of the said arms with the end piece 21 as the same is positioned within the die mechanism of the press operating elements. Inasmuch as the result of this movement of the arms 96 and 97 upon end piece 21 differs according to the different positions of the same, the action upon an end piece in three different positions will now be described in connection with Figs. 5, 6, and 7.

At the station C, the arms 96 and 97 assume their closed positions irrespective of the different gauging results on the end pieces 21. In Fig. 5 there is illustrated an end piece 21 positioned with its *x* axis in alignment with the longitudinal central axis of the cut edge 25 of the die mechanism. At such time the projection 101 is in engagement with an inclined surface *e* joining the edges *d* and *c*, and the finger 108 held by the spring 112 in locked position against the edge of the arm 97 has engaged a slotted edge *f* joining the edges *b* and *c*.

The outer extremity of the finger 108 rest-

ing within the slot *f* of the end piece 21 and the outer extremity of the projection 101 resting against the inclined surface *e* of the said end piece properly positions the latter longitudinally over the die parts. The upper dog 73 during this gauging action forms the reference point for the rear edge *d* of the end piece 21 and in such position the *y* axis of the said end piece is brought into proper coordination with the vertical central axis of the cut edge 25 of the press mechanism. At such time, the lower edge *a* of the end piece 21 is positioned against a side guide rail 121 secured by screws 122 to the upper surface of the table 46. This guide rail is not engaged by the end piece 21 as it is moved along the upper surface of the table 46 through stations A and B, inasmuch as gravity tends at all times to hold the said end piece 21 with its edge *c* against the sliding bar 76, as previously described.

Where the end piece 21 is brought into the apparatus with its edge *c* against the bar 76 and its rear edge *b* engaged by the feed dog 73, the operation of the gauging and checking device is slightly different. In the final gauged position of the said end piece 21 at the station C, the notched edge *f* is engaged by the outer extremity of the projection 101 and the outer extremity of the finger 108 engages the inclined face *e* of the said end piece 21. At such time, the edge *a* is brought into contact with the guide rail 121.

As illustrated in Fig. 6, when an end piece 21 is positioned as just described, the finger 108 is caused to pivot about the point 111 against the action of the spring 112 and the face of the said finger 108 is withdrawn from the forward edge of the arm 97. In this held position, the *x* axis of the strip 21 coincides with the longitudinal center of the cut edge 25 of the die mechanism and the *y* axis of the same properly cooperates with the vertical center of the said cut edge. The upper dog 73 in this position engages the rear edge *b* of the end piece 21.

Where the end piece 21 is received into the apparatus with its edge *a* resting against the bar 76, the gauging and checking device will assume a slightly different relation relative thereto. As the end piece 21 is properly positioned over the die mechanism at the station C under such circumstances, there is no shifting of the longitudinal center *x* relative to the bar 76, and the edge *a* of the end piece 21 remains in contact with said bar. This condition properly positions the end piece 21 with its *x* axis in alignment with the longitudinal center of the cut edge 25 of the die mechanism and no longitudinal shifting of the end piece 21 takes place. The lateral position of the end piece under these circumstances is insured by the cooperation of the inner face of the finger 108 engaging a straight edge *g* of the end piece 21, and the lower feed

dog 73 engaging the edge *b*. During this gauging operation, it should be evident that the projection 101 does not operate in any manner upon the end piece 21, there being no engagement of the said projection with any edge of the said end piece.

There is also a fourth position which the end piece 21 can occupy as it is moved through stations A, B, and C. This position as occupied by the end piece 21 at the station A is illustrated in Fig. 1. The upper edge *a* of the end piece in such position is held by gravity against the sliding bar 76 and the rear edge *d* is moved by the lower set of dogs 61 and 73 as the end piece moves from station A to station B, and later from station B to station C. The final position at station C of the end piece 21 is very similar to the position of the end piece illustrated in Fig.

7. The *x* axis is in alignment with the longitudinal axis of the die mechanism and the *y* axis is aligned with the vertical axis of the die apparatus by cooperation of the lower feed dog 73 engaging the edge *d* of the strip 21 and the finger 108 held in normal position against the arm 97 by the spring 112 engages an edge *h* of the said end piece. At such a time the arm 96 is in the same position as is shown in Fig. 7, and the projection 101 thereof is out of contact but adjacent to the edge *g* of the end piece.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a gauging and checking attachment for a press, the combination of press operating elements, feeding means for receiving non-symmetrical end pieces in any one of a number of different positions and moving the same to said press operating elements, and gauging and checking devices for positioning said end pieces into said press operating elements according to the position of said end pieces.

2. In a gauging and checking attachment for a press, the combination of press operating elements, feeding means for receiving non-symmetrical end pieces in any one of a number of different positions and moving the same to said press operating elements, and gauging and checking devices for simultaneously positioning said end pieces into said press operating elements according to the position of said end pieces.

3. In a gauging and checking attachment for a press, the combination of press operating elements, a feed table for receiving non-

symmetrical end pieces in any one of a number of different positions, feeding means for moving said end pieces along the feed table to the press operating elements, and gauging and checking devices for positioning said end pieces into said press operating elements according to the received position of said end pieces.

4. In a gauging and checking attachment for a press, the combination of press operating elements, feeding means for first receiving end pieces non-symmetrical as to their *x* and *y* axes and in different axial relation to said feeding means, and second, moving said end pieces to said press operating elements and gauging and checking devices for positioning said end pieces into proper axial coordination with the said press operating elements.

5. In a gauging and checking attachment for a press, the combination of press operating elements, a feed table for receiving non-symmetrical end pieces in any one of a number of different positions, primary feeding means for placing said end pieces upon said table, secondary feeding means for moving said end pieces along the table to said press operating elements, and gauging and checking devices for positioning said end pieces into said press operating elements according to the received position of said end pieces.

6. In a gauging and checking attachment for a press, the combination of press operating elements, a feed table for receiving non-symmetrical end pieces in any one of a number of different positions, primary feeding means for placing said end pieces upon said table, secondary feeding means for moving said end pieces along the table to said press operating elements, and gauging and checking devices, simultaneously operating with the operation of said secondary feeding means, for positioning said end pieces into said press operating elements according to the received position of said end pieces.

7. In a gauging and checking attachment for a press, the combination of press operating elements, a feed table for receiving non-symmetrical end pieces in any one of a number of different positions, continuously operating feeding means for placing said end pieces upon said table, reciprocating feeding means for moving said end pieces along the table to said press operating elements, and gauging and checking devices for positioning said end pieces into said press operating elements according to the received position of said end pieces.

8. In a gauging and checking attachment for a press, the combination of press operating elements, a feed table for receiving non-symmetrical end pieces in any one of a number of different positions, feeding means for moving said end pieces along the feed table to the press operating elements, and gauging

and checking devices moving with said feeding means and with a said end piece carried thereby for laterally and longitudinally shifting said end piece during such movement to place the same into said press operating elements in a one proper position.

9. In a gauging and checking attachment for a press, the combination of press operating elements, a feed table for receiving non-symmetrical end pieces in any one of a number of different positions, feeding means for moving said end pieces along the feed table to the press operating elements, and gauging and checking devices comprising a plurality of pivotal arms moving with said feeding means and with a said end piece carried thereby for laterally and longitudinally shifting said end piece during such movement for placing the same into said press operating elements in a one proper position.

10. In a gauging and checking attachment for a press, the combination of press operating elements, a feed table for receiving non-symmetrical end pieces in any one of a number of different positions, feeding means for moving said end pieces along the feed table to the press operating elements, and gauging and checking devices comprising a plurality of pivotal arms moving with said feeding means and with a said end piece carried thereby, said arms having projections movable into contact with said end piece for laterally and longitudinally shifting the same and placing it into said press operating elements in a one proper position.

11. In a gauging and checking attachment for a press, the combination of press operating elements, a feed table for receiving non-symmetrical end pieces in any one of a number of different positions, feeding means for moving said end pieces along the feed table to the press operating elements, gauging and checking devices comprising a plurality of pivotal arms moving with said feeding means and with a said end piece carried thereby, and cam means for holding said arms out of the path of travel of said end piece as the same is brought adjacent said arms but permitting pivotal action of said arms during the forward movement thereof to cause projections carried by said arms to move into contact with said end piece and laterally and longitudinally shift the same and place it into said press operating elements in a one proper position.

12. In a gauging and checking attachment for a press, the combination of press operating elements, a feed table for receiving non-symmetrical end pieces in any one of a number of different positions, feeding means for moving said end pieces along the feed table to the press operating elements, and gauging and checking devices for laterally and longitudinally shifting said end

piece to place the same into said press operating elements in a one proper position.

13. In a gauging and checking attachment for a press, the combination of press operating elements, feeding means for receiving non-symmetrical end pieces and moving them to the press operating elements and gauging and checking devices cooperating with the feeding means for moving the end piece sidewise to a one proper position within the press operating elements.
